UNITED STATES PATENT OFFICE.

ARTHUR FREDERICK RICHMOND COTTON, OF LONDON, ENGLAND.

GRAMOPHONE.

Application filed June 11, 1923. Serial No. 644,648.

To all whom it may concern:

Be it known that I, ARTHUR FREDERICK RICHMOND COTTON, research student, of 9 Wetherby Gardens, London, S. W. 5, England, have invented certain new and useful Improvements in Gramophones, of which the following is a specification.

This invention relates to gramophones and the like, and has for its object to provide an improved resetting device for effecting the repetition of a record or passage, by raising the soundbox, returning the tone-arm, and lowering the needle again into contact with the record disc.

More particularly the object of the invention is to provide a simple mechanical device for resetting the gramophone, by means of a blow delivered by a projection on the revolving turn-table, this projection acting upon a movable member carried by a displaceable bar which can engage the soundbox.

The invention has also for its object to ensure the definite operation of the resetting mechanism at the selected point, by providing a trigger device which gives a sudden movement consequent upon a preliminary engagement with the turn-table.

The invention is hereafter described with reference to the accompanying drawings, in which:

Figure 1 is a plan view of the turn-table and tone-arm of a gramophone, provided with the resetting device, the position represented being that of the parts at the commencement of the record.

Figure 2 is a similar view showing the parts at the end of the record, the resetting action being about to take place.

Figure 3 is a plan of the friction wheel which makes the preliminary engagement with the turn-table.

Figure 4 is an elevation corresponding to Figure 2.

Figure 5 is a detail on a larger scale, viewed towards the right of the line $x-x$ in Figure 4.

Figure 6 is a detail, also on a larger scale, viewed towards the left of the line $x-x$ in Figure 4.

Figure 7 is a detail of the movable member adapted to be struck by the projection on the turn-table.

Figure 8 is a detail of a modification in which the friction wheel itself carries the

movable member engaged by the projection on the turn-table.

Figure 9 is an inverted plan of a portion of the turn-table, showing an alternative form of projection and illustrating its engagement with the movable member.

Figure 10 illustrates the lifting of the soundbox when the resetting device comes into operation.

Figure 11 illustrates a suitable construction of automatic brake for terminating the repetition at the end of the record.

Figure 12 is a detail of the resetting mechanism.

Referring to Figures 1 to 7, the tone-arm a is shown supported by a bridge b secured to the top board of the instrument, and the soundbox c is mounted upon a swan neck fitting d in the usual manner. The tone-arm is provided with a lug a' and the T piece of the swan neck with another lug d' ; these two lugs provide bearings for a displaceable bar e which extends longitudinally beneath the tone-arm and is adapted to rock in its bearings.

One end of the bar e carries a cam or wedge member f having its upper beveled face f' lying beneath the sound box when the latter has its needle c' in position upon the record disc g ; the dimensions of the cam f are such that by rocking through an angle of 45 degrees for example, it acts to lift the sound box as shown in dotted lines in Figure 10 and raise the needle clear of the record disc.

At the opposite end of the displaceable bar e , there is provided a double catch e^2 which can be engaged in either of two positions by a detent h controlled by a spring h^3 (see Figure 12) and pivoted upon the lug a' dependent from the tone-arm a ; in the first position of the bar e (see dotted lines in Figure 5), the face f' is clear of the soundbox (as seen in Figure 4), but in the second position (see full lines in Figure 5) the detent h holds the bar in its rocked position with the soundbox raised by the cam f . A pin h^2 projects from the web a' and limits the movements of the detent h .

The portion of the bar e comprised between the lug d' and the catch e^2 is preferably of square section, to receive a slidable carriage i supporting the movable member which produces the rocking motion of the bar when the re-setting is to take place.

The carriage i is provided with a small pinion or milled wheel i' (Figure 6) engaging with a correspondingly toothed or milled face of the bar e , this pinion being revoluble by means of a knob i^2 for the purpose of shifting the carriage i along the bar, and a spring i^3 acts as a brake to hold the carriage in the set position.

Beneath the carriage i and at the level of the rim of the turn-table j , there is mounted a rubber-tyred wheel or roller k adapted to engage the turn-table when the travel of the tone-arm brings it into contact therewith, the point of engagement which initiates the re-setting action being variable according to the position of the slideable carriage. The wheel k is preferably eccentric, so that when it first engages the rim of the turn-table, the pressure between them increases automatically to ensure firm contact, even if the rim of the turn-table should not be truly circular. This wheel k (see Figure 3) is pivoted or revoluble upon a stud k^1 and provided with two upstanding pins k' which limit its movement by their abutment against either side of a web i^4 on the carriage, and also with a radially outstanding crank arm k^2 which (as seen in Figure 2) is adapted to advance a movable member which is here shown as an intermediate lever i^5 pivoted to and dependent from the web i^4 at i^6 . This lever i^5 is of inverted L-shape and it is weighted at its upper part so that its dependent leg will normally hang vertically from its pivot i^6 close to the periphery of the wheel k . This leg of the lever i^5 is adapted to be struck by a projection l upon the revolving turn-table when the lever i^5 has been advanced into the path of the projection by the action of the crank arm k^2 . This projection l in its rotation with the turn-table, passes under the wheel k (as seen in Figure 4); but when the crank arm k^2 has been swung round by the rotation of the friction roller k , it interposes the intermediate lever i^5 in the path of the projection l , so that at its next revolution the projection from the turn-table will strike the movable member or lever i^5 . The displaceable bar e will therefore be rocked to the position of Figure 5, in which it is held by the detent h , the soundbox being at the same time raised by the cam f . The impact of the blow also causes the tone-arm to swing back towards the starting point, or—if desired—a spring a^2 or weight may be employed in the known manner for effecting the return movement of the tone-arm.

It is to be noted that in Figure 2 the soundbox has moved transversely across the record disc, as compared with Figure 1, the pin k' in Figure 2 contacting with the web i^4 , so that the roller k remains stationary its crank arm k^2 holding the lever i^5 in the path of the projection l .

The wheel k is put out of balance, for example, by providing a number of holes k^3 , so that as soon as the arm i^5 escapes from the projection l , the wheel returns to its original orientation, its axis being at that time oblique owing to the rocking of the bar e . The weighted lever i^5 also resets itself and assists in restoring the wheel k .

An adjustable stop m , consisting of a spring plunger adapted to slide in a cylindrical guide m^3 upon a supporting bracket m' and normally secured at any desired position by a clamping lever m^2 in the form of a bell crank with very unequal arms, controlled by a spring m^4 , is arranged upon the top board of the instrument in line with the arcuate movement of the detent h ; for setting the point at which the repetition is to commence, the needle is placed upon the record disc at the desired position, and the spring plunger then allowed to project until it engages the tail h' of the detent, the plunger being automatically locked as soon as the lever m^2 is released.

When the return of the tone-arm brings the detent h h' into contact with the stop-plunger m the catch e^2 is released; the bar e then resumes its normal position, allowing the soundbox e to descend upon the record. The descent is preferably retarded by means of a cam or eccentric quadrant f^2 of the known kind, pivoted upon the wedge or cam f , so that when the bar e allows the needle to descend, the quadrant f^2 trails upon the revolving record and lowers the needle gently into position.

It will be noted that the longitudinal bar e is weighted by the wheel k , knob i^2 and other parts, so that it resumes its normal position as soon as the detent h releases the catch e^2 .

The design of the arm i^5 supported from the tone-arm may be varied; for example it may be inclined or curved at an angle of approximately 45 degrees, so that instead of receiving a direct blow it is moved gradually by the pawl or projection.

Figure 8 represents a modified construction of the friction wheel k , in which the latter is provided with a dependent pin k^5 which forms the movable member, being adapted to be brought into the path of the projection l (as shown in dotted lines) when the wheel is rotated by its frictional engagement with the turn-table.

The projection l is shown in Figures 1, 2, 4 and 8, as a small roller mounted upon a stud or pin outstanding from the rim of the turn-table. In Figure 9 I have represented an alternative form, in which a pawl l' is pivoted on a pin l^2 , and controlled by a spring l^3 ; as soon as this pawl l' engages the arm it is brought against the stop pin l^4 , its free end being simultaneously moved outwardly away from the periphery of the

turn-table, as shown in dotted lines, the rotation of the turn-table then producing a full movement of the arm and connected parts.

- 5 A suitable automatic brake device may be provided for stopping the turn-table when the reproduction is to be discontinued, the stop m being re-adjusted for this purpose to allow the needle to fall clear of the record disc at the next operation of the mechanism. Figure 11 illustrates a convenient arrangement in which a lever o fulcrumed at o' upon the instrument has at one end a brake shoe o^2 adapted to engage 10 the turn-table j , and at the other end a pad o^3 upon which the needle or soundbox can rest, the weight of the soundbox then acting to press the brake shoe into contact with the turn-table, against the action of a spring 15 o^4 .

Having thus described my invention, what I claim is:—

1. In a gramophone, a turn-table, a travelling tone-arm, a soundbox arranged at 25 one end of said tone-arm, a pivotal support for the tone-arm so that the soundbox can travel across a record disc located on the turn-table, means carried by the tone-arm for lifting the soundbox, means dependent 30 from the travelling tone-arm for preliminarily engaging the revolving turn-table, a pivoted device carried by said tone-arm, said device as a result of such preliminary engagement being moved into position to 35 be operated by the turn-table, and means carried by the turn-table for engaging said pivoted device, said pivoted device there-upon operating said lifting means.

2. In a gramophone, a rotatable turn-table, a projection from said turn-table, a travelling tone-arm having at one end a pivotal bearing and at the other end a soundbox, a displaceable bar carried by said tone-arm, means carried by the bar for engaging and lifting the soundbox as a result of a movement imparted to said displaceable bar, a movable member carried by the said bar and adapted to impart movement thereto, and means whereby said movable member is engaged and operated by the projection from the turntable.

3. In a gramophone, a rotatable turn-table, a projection from said turn-table, a travelling tone-arm fitted with a soundbox, a pivotal mounting for said tone-arm whereby the soundbox, can travel transversely of the record, bearings upon said tone-arm, a displaceable bar carried in said bearings, means carried by the bar for engaging and lifting the soundbox and a movable member also carried by the tone-arm and adapted to be actuated by the projection from the turn-table, said bar-displacing means being operated by the actuation of the said movable member carried by the tone-arm.

4. In a gramophone, a rotatable turn-table, a projection from said turn-table, a travelling tone-arm having a soundbox at one end and being pivotally mounted at the other end, a displaceable bar carried by the tone-arm with one end adjacent to the soundbox, means provided upon that end of the bar for engaging and lifting the soundbox, a lever controlling the displacement of said bar, a friction wheel, carried by the tone-arm and adapted to be brought into operative contact with the revolving turn-table during the travel of the tone-arm, and means provided upon said friction wheel for bringing said lever into the path of said projection to actuate the displaceable bar.

5. In a gramophone of the type having a rotatable turntable and a tone-arm swinging so that its soundbox can travel transversely across the record disc, a resetting mechanism 85 comprising a movable member carried by said tone-arm, a projection on the rim of said turn-table, a displaceable bar travelling with said soundbox and adapted to lift its needle from the record, said movable member actuating said displaceable bar, means for bringing said movable member into the path of said projection, and means for returning the tone-arm towards the starting point.

6. In a gramophone of the type having a rotatable turntable and a tone-arm swinging so that its soundbox can travel transversely across the record disc, a resetting mechanism comprising a movable member 100 carried by said tone-arm, a projection on the rim of said turntable, a displaceable bar travelling with said soundbox, means carried by said displaceable bar for lifting the needle from the record, said movable member actuating said displaceable bar, means for bringing said movable member into the path of said projection, and means for restoring said displaceable bar to its original position at the starting point.

7. In a gramophone, the combination of a tone-arm swinging transversely across a record disc, a displaceable bar rockable in bearings beneath said tone-arm, means carried by said bar for raising the soundbox, a carriage adjustable along said bar, a friction wheel revolvably mounted on said carriage, said wheel adapted to engage the turntable towards the end of the record, a movable member controlled by said friction wheel and adapted to be engaged by a projection on the turntable, the engagement of said movable member by said projection causing the displacement of said bar and the lifting of the soundbox, and means for restoring said bar to its original position at the starting point.

8. In a gramophone resetting mechanism, the combination of a turntable, a projection on said turntable, a displaceable bar adapted 130

to engage the sound box and lift the needle from the record, means for displacing said bar, said means actuated by a blow delivered by the said projection when resetting is by the said projection when the resetting is 5 to take place, a detent for retaining said bar in its displaced position during the return movement of the soundbox, a stop for releasing said detent on arrival at the re-starting point, and a spring plunger automatically adjusting said stop when released 10 with the needle at the desired starting position.

9. In a gramophone resetting mechanism, the combination of a turntable, a projection 15 on said turntable, a rockable bar, a cam at one end of said bar, said cam adapted to engage the soundbox and lift the needle

from the record, means for rocking said bar, said means actuated by a blow delivered by the said projection when resetting is to take 20 place, a catch secured upon said bar at the opposite end to said cam, a detent co-operating with said catch to retain said bar in either of two positions corresponding respectively to the raising and to the lowering 25 of the needle, a stop for releasing said detent on arrival at the re-starting point, and means for automatically adjusting said stop when the needle is placed at the desired 30 starting position.

In testimony whereof I have hereunto affixed my signature.

ARTHUR FREDERICK RICHMOND COTTON.
